Primary Examiner — Richard Edgar

Assistant Examiner — Courtney J Clark-Rasheed

(57) **CLAIM**

The ornamental design for a cup cover as shown and described.

DESCRIPTION

FIG. 1 is a front perspective view of a cup cover showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a front perspective view thereof, showing the cup cover in a state of use; and,

FIG. 10 is a rear perspective view thereof, showing the cup cover in a state of use.

The broken lines in the drawings depict portions of the cup cover that form no part of the claimed design.

The straw shown in broken lines in FIGS. 9 and 10 depicts environment which forms no part of the claimed design.

1 Claim, 10 Drawing Sheets
